THERAPEUTIC ARYL AND THIENYL HYDROXYLAMINES

John H. Biel and Jerry E. Robertson, both of Milwaukee, Wis., assignors to Colgate-Palmolive Company, a corporation of Delaware
No Drawing. Filed Apr. 24, 1962, Ser. No. 189,722
8 Claims. (Cl. 167—65)

This invention relates to aralkyl derivatives and uses therefor. More particularly, this invention is concerned with therapeutic uses for O-arylhydroxylamines and pharmaceutical compositions for such uses.

This application is a continuation-in-part of copending application Serial No. 85,979, filed January 31, 1961, and now abandoned.

According to the present invention it has been found that O-phenylalkylhydroxylamines and O-thienylalkylhydroxylamines of the formulae

and

wherein R is hydrogen or at least one substituent of the group consisting of hydroxy, halogens such as bromine and chlorine, trifluoromethyl, lower alkoxy groups such as methoxy, ethoxy and propoxy, lower alkylenedioxy such as 3,4-methylenedioxy, nitro and acyloxy groups from carboxylic acids as where R represents

where R₁ is a lower alkyl such as methyl and ethyl, phenyl and a phenyl-lower alkyl such as benzyl and phenethyl, and Y is a straight or branched lower alkylene, advisably of not more than five carbons, such as methylene, ethylene, propylene and isopropylene, have DOPA decarboxylase inhibitory activity. DOPA is, of course, beta-(3,4-dihydroxyphenyl)-L-alanine.

Because of the DOPA decarboxylase inhibitory activity of these compounds, they are useful hypotensive and tranquilizing agents when administered in nontoxic chemotherapeutic amounts. The levels of gamma aminobutyric acid (GABA) in the brain could also be raised by the administration of these compounds and, thus, they can be useful anticonvulsants.

The invention is particularly concerned with the compounds of the formulas

and

wherein R has the assigned meaning, since these compounds are not only DOPA decarboxylase inhibitors but are also inhibitors of dopamine beta-oxidase.

The inhibition of the enzyme DOPA decarboxylase prevents the decarboxylation of dihydroxyphenylalanine (DOPA) to dihydrophenylethylamine (dopamine) and of 5-hydroxy-tryptophan to 5-hydroxytryptamine (serotonin). The inhibition of dopamine β -oxidase prevents the β -hydroxylation of dopamine to norepinephrine. Since

2

the over-all effect of this dual enzyme inhibition is a depletion of serotonin, norepinephrine and epinephrine stores in the body, these compounds would be expected to produce significant therapeutic effects in hypertension and in the treatment of anxiety and mental depression. Since certain oxidation products of epinephrine such as adrenochrome and adrenolutin are thought to be implicated in the etiology of schizophrenia, such drugs might also be of value in the treatment of psychotic states.

10 The compounds in which Y is of three or more carbons are indicated to be local vasoconstrictors, central stimulants, cardiac stimulants and analeptic agents. The mood lifting properties of the compounds indicates their use in the treatment of mental depression. Relief of anxiety 15 (tranquillization) produces a calming effect.

O-benzylhydroxylamine and a process for its production is shown by Theilacker et al. in *Angewandte Chemie*, 68, 303 (1956) and *Chem. Abstr.* 52, 15454 (1958). This reaction can be represented as follows, as well as its 20 application to the preparation of O-thienylmethylhydroxylamines:

30 wherein R has the significance assigned above.

Some of the aralkanols that can be used in the process are benzyl alcohol, p-nitrobenzyl alcohol, 2,6-dimethoxybenzyl alcohol, 3,4-methylenedioxybenzyl alcohol, p-hydroxybenzyl alcohol, 2-thienylmethyl alcohol and 3-thienylmethyl alcohol.

Representative of the compounds of this invention which are produced as described are O-benzylhydroxylamine, O-(2,6-dimethoxybenzyl)-hydroxylamine, O-(3,4-methylenedioxybenzyl)-hydroxylamine, O-(p-hydroxybenzyl)-hydroxylamine, O-(2-thienylmethyl)-hydroxylamine and O-(3-thienylmethyl)-hydroxylamine.

A general method of producing the O-phenylalkylhydroxylamines, and a process which is equally applicable to production of the O-thienylalkylhydroxylamines, comprises reacting a phenylalkyl halide with hydroxyurethane to form a O-phenylalkylhydroxylurethane which, upon hydrolysis, yields a O-phenylalkylhydroxylamine. This process can be represented as follows:

65 wherein X is a reactive halogen and R and Y have the assigned meaning. This process is described by A. T. Fuller et al. in *J. Chem. Soc.* 963 (1947) and it was used by Major et al. in *J. Med. Pharm. Chem.* 4, 51 (1961) to make O-(beta-phenethyl)-hydroxylamine.

70 The compounds in which Y is a lower alkylene having at least two carbons appear to be novel.

Another convenient route to the O-substituted hy-

droxylamines is through benzohydroxamic acid according to the scheme

wherein R, X and Y have the significance previously assigned and ϕ is phenyl. Fuller et al supra also illustrate this route.

A convenient reference to the various preparations of O-substituted hydroxylamines is C. D. Hurd in Gilman, *Organic Chemistry*, 1st ed., vol. 1, John Wiley & Sons, Inc., N.Y., 1938, pp. 677-679.

Some of the compounds which are readily produced by these methods are O-phenylisopropylhydroxylamine, O-[2-(1-phenylpropyl)]-hydroxylamine, O-[2-(3-thienyl)-ethyl]-hydroxylamine and O-1-[2-(2-thienyl)-propyl]-hydroxylamine.

The O-alkylhydroxylamines with which this invention is concerned form acid addition salts with organic and inorganic acids such as hydrochloric acid, sulfuric acid, phosphoric acid, citric acid, maleic acid, tartaric acid, fumaric acid and glutamic acid.

The O-alkylhydroxylamines can be administered as the base, or in the form of a nontoxic acid addition salt, as a unit dosage in pure undiluted form to obtain the desired therapeutic effect. However, it is desirable in most instances to administer the compounds combined with a suitable pharmaceutical carrier or diluent to achieve a more convenient size to dosage relationship.

Pharmaceutical unit dosage forms can be readily produced by intimately mixing one or more of the compounds with a suitable pharmaceutical carrier. The carrier can be either a liquid or a solid. When a liquid is used either a solution or a suspension can be produced. Flavoring substances may be included as desired. Sterile water is the preferred liquid carrier; it readily dissolves the salts to form solutions.

Solid pharmaceutical carriers such as starch, sugar and talc can be used to form powders. Such powders can be tableted by the use of suitable lubricants such as magnesium stearate, binders such as gelatin and disintegrating agents like sodium bicarbonate in combination with citric or tartaric acid.

A typical hard gelatin capsule can have the composition:

	Mg.
O-benzylhydroxylamine HCl	50
Lactose	200
Starch	16
Talc	8

The preferred route of administering the O-alkylhydroxylamines is oral and for this method tablets and capsules are ordinarily recommended. The unit-dosage compositions can contain from about 25 mgm. to 1000, and advisably 50 to 200 mgm. of the active compound with the dosage determined in view of the activity of the particular O-alkylhydroxylamine used as well as the contemplated administration per day. In general, daily administration of 100 mgm. to 4000 mgm. achieves the therapeutic effects given above.

The following examples are presented to illustrate the preparation of the compounds concerned in this invention.

EXAMPLE 1

O-benzylhydroxylamine hydrochloride

An ethereal solution of monochloroamine was prepared by mixing at 0-5° C., 414 ml. of 4.15 N sodium hypo-

chlorite and 902 ml. of 1.79 N ammonium hydroxide and extracting with three 300 ml. portions of ether. The combined ethereal extracts were dried over calcium chloride and utilized as described below. Sodium (11.5 g., 0.50 mole) was dissolved with warming in a mixture of 260 ml. dry benzyl alcohol and 200 ml. of dry dioxane held in a 1 liter round bottom flask equipped with a stirrer, condenser, and ice jacketed dropping funnel. At a solution temperature of 75-85° C. all of the ethereal monochloramine (ca. 0.5 mole) solution, prepared as described above, was added at such a rate that the ether could be conveniently stripped through a 50 cm. packed column. Care was taken during the addition to avoid allowing the chloramine solution to touch the hot sides of the reaction vessel. The addition required about 1 hour and the temperature was maintained for an additional 0.5 hour. The apparatus was adjusted for direct distillation and the solvents were removed under water aspirator vacuum. The residue was filtered to remove sodium chloride and then distilled at less than 1 mm. (ca. 65-75° C./0.2 mm.) until only a gum remained as a residue. The distillate was treated with ethereal hydrogen chloride until precipitation was completed and the crude product collected. Recrystallization from methanol-n-hexane afforded 38 g. (50%) of product, M.P. 230-255° C. (sublimes) reported M.P. 200-250° C. and 230-260° C.

Analysis.—Calcd. for $C_7H_{10}NOCl$: Chloride, 22.22. Found: Chloride, 22.22.

EXAMPLE 2

O-p-methoxybenzylhydroxylamine hydrochloride

To a solution of 70 g. (0.5 mole) of p-methoxybenzyl alcohol in 100 ml. of dioxane was added 2.3 g. (0.1 mole) of sodium. After all of the sodium had reacted, the mixture was heated to 80-90° C. and about 325 ml. of ether solution containing about 0.1 mole of monochloramine (pre-dried with calcium chloride) was added at such a rate that the ether could be conveniently distilled off through an 18" glass-packed column. The addition time was about 30 minutes. The mixture was cooled, filtered and the solvent removed under reduced pressure on a water bath. The residue was distilled rapidly at less than 1 mm. with a major fraction distilling at 65-70° C./0.3 mm. Dilution of the total distillate with about half its volume of ether followed by addition of excess ethereal HCl and cooling gave a solid which was collected, washed with ether and dried to afford 8.5 gm. (45%) of the product, M.P. 208-210° C.

Analysis.—Calcd. for $C_8H_{12}NO_2Cl$: Cl, 18.73; N, 7.39. Found: Cl, 18.89; N, 7.14.

Various changes and modifications of the invention can be made and, to the extent that such variations incorporate the spirit of this invention, they are intended to be included within the scope of the appended claims.

What is claimed is:

1. A pharmaceutical composition in unit dosage form comprising from 25 to 1000 mgm. of a member of the group consisting of compounds of the formula

65 and

70 wherein R is at least one member of the group consisting of hydrogen, hydroxy, halogen, trifluoromethyl, lower alkoxy, lower alkyleneedioxy, nitro and

5

wherein R_1 is a member of the group consisting of lower alkyl, phenyl and phenyl-lower alkyl, and Y is lower alkylene having at least two carbons, and a pharmaceutical diluent.

2. A pharmaceutical composition in unit dosage form comprising from 25 to 1000 mgm. of O-phenyl-lower alkyl hydroxylamine wherein said lower alkyl has at least two carbons, and a pharmaceutical diluent.

3. A pharmaceutical composition in unit dosage form comprising from 25 to 1000 mgm. of O-thienyl-lower alkyl hydroxylamine wherein said lower alkyl has at least two carbons, and a pharmaceutical diluent.

4. The method of inducing a hypotensive effect which comprises orally administering to an animal suffering with hypertension a nontoxic chemotherapeutically effective amount of a member of the group consisting of compounds of the formulas

and

wherein R is at least one member of the group consisting of hydrogen, hydroxy, halogen, trifluoromethyl, lower alkoxy, lower alkylenedioxy, nitro and

wherein R_1 is a member of the group consisting of lower alkyl, phenyl and phenyl-lower alkyl, and Y is lower alkylene.

5. The method of claim 4 in which about 100 to 4000 mgm. of the compound as defined therein is administered in unit dosage form per day.

6. The method of treating mental depression and anxiety which comprises orally administering to an animal suffering with mental depression and anxiety a nontoxic

5

chemotherapeutic amount of a member of the group consisting of compounds of the formulas

and

wherein R is at least one member of the group consisting of hydrogen, hydroxy, halogen, trifluoromethyl, lower alkoxy, lower alkylenedioxy, nitro and

wherein R_1 is a member of the group consisting of lower alkyl, phenyl and phenyl-lower alkyl, and Y is lower alkylene.

7. The method of claim 6 in which about 100 to 4000 mgm. of the compound as defined therein is administered in unit dosage form per day.

8. The method of inducing a hypotensive effect which comprises orally administering about 100 to 4000 mgm. of O-benzylhydroxylamine to an animal per day.
